UNITED STATES PATENT OFFICE.

PETTER B. ABRAMSEN, OF KNOXVILLE, PENNSYLVANIA.

MACHINE FOR STRAIGHTENING RODS AND PIPES.

1,097,281.

Specification of Letters Patent.

Patented May 19, 1914.

Application filed April 15, 1913. Serial No. 761,294.

To all whom it may concern:

Be it known that I, PETTER B. ABRAMSEN, a subject of the King of Norway, residing at Knoxville, Allegheny county, Pennsylvania, have invented a new and useful Improvement in Machines for Straightening Rods and Pipes, of which the following is a full, clear, and exact description, reference being had to the accompanying drawings, forming part of this specification, in which—

Figure 1 is a plan view of a machine embodying my invention; Fig. 2 is a section on the line II—II of Fig. 1; Fig. 3 is a section on the line III—III of Fig. 1, but with the driving mechanism omitted; Fig. 4 is a perspective view of one of the adjusting wedges; Fig. 5 is a longitudinal section of one of the longer cross-rolls; Fig. 6 is a longitudinal section of one of the shorter cross-rolls with the rolling shaft removed; and Fig. 7 is a detail view showing a modification.

My invention has relation to the class of pipe and rod-straightening machines; and is designed to provide a simple and efficient machine of this character by means of which the straightening of rods and pipes can be effected in a better manner than heretofore.

In straightening round bars, rods and pipes, it has been customary heretofore to revolve the bar, rod or pipe to be straightened between a pair of cross-rolls, the bar, rod or pipe revolving and advancing through the rolls in a spiral line. It has been found that in these machines, the rod has a constant tendency to move laterally, or to assume a position parallel to the axis of one or the other of the rolls. In this manner the effect of the pressure from the rolls is partly lost, and the rod or pipe is not properly straightened. In view of this tendency, it has been customary to provide straightening machines employing cross rolls with a more or less complicated system of guides designed to hold the bars to a straight path. These, however, are objectionable, not only because they complicate the construction of the machine, but also because they mark the bars or other objects being straightened, being required to exert considerable force in order to prevent deflection of the bars.

My invention is designed to overcome this difficulty, and it consists in the provision of two separated sets of cross-rolls, between which the rod or pipe is passed, and by which it is rigidly held at two separated points. Each set of cross rolls forms a

straightening pass, and these passes coact to hold the bar or pipe being straightened against movement to one side of the axial line of the said passes without auxiliary guiding means. Intermediate of the two sets of cross-rolls, I preferably provide a relatively short pressure roll, which is preferably made adjustable for it to give any desired degree of pressure on the rod or pipe intermediate the two sets of cross-rolls.

Referring to the accompanying drawings, in which I have shown the preferred embodiment of my invention, which will now be described, the numeral 2 designates the frame of the machine, which may be of any suitable character.

3 and 4 designate the rolls of one pair of cross-rolls, and 5 and 6 the rolls of the second pair of cross-rolls. The rolls 3 and 5 are constructed with a reducing taper from each end toward the center. The rolls 4 and 6 are preferably considerably shorter than the rolls 3 and 5 and are formed with substantially straight bearing portions which are respectively opposite the centers of the rolls 3 and 5. The construction and arrangement of the two rolls of each set or pair is such that the piece to be straightened has two separated bearings on each of the longer rolls, while the shorter roll has a central bearing on the piece intermediate the two bearing points of the longer roll. The longer rolls are sufficiently reduced in diameter at their centers so as to give a clearance or bending space opposite the bearing portions of the shorter rolls. The rolls 3 and 5 are mounted on the parallel skew shafts 7 and 8, which are journaled in suitable bearings 9 of the frame 2. The rolls 4 and 6 are journaled on short skew shafts 10, mounted in yokes 11, adapted for both longitudinal and lateral adjustment on the portion 2^a of the frame. To provide for this adjustment, the outer portion of each yoke is provided with the horizontal slots 12, and the portion 2^a of the frame is formed with the longitudinal slots 13. These two slots intersect with each other, and the yokes are secured in the proper adjustment by means of bolts 14. For the purpose of adjusting the yokes laterally, I provide the longitudinally extending screw shaft 15 having thereon wedge blocks 16, which, when the shaft 15 is rotated, are adapted to force the yokes inwardly and thus move the rolls 4 and 6 toward the rolls 3 and 5.

10 15 20 25 30 35 40 45 50 55 60 65 70 75 80 85 90 95 100 105 110

17 designates a pressure roll located intermediate the two sets of cross-rolls and between the two rolls 4 and 6. This roll 17 is mounted in a yoke 18, which is similar to the yokes 11 before described, and is adjustable in the same manner, the shaft 15 having thereon a third wedge block 19, which actuates the yoke 18.

The rolls 3 and 5 are positively driven in any suitable manner. In the drawing I have shown this as being effected by an electric motor at 20, whose armature shaft carries a pinion 21 meshing with a gear wheel 22 on an intermediate shaft 23. This intermediate shaft carries a pinion 23^a which drives a gear wheel 23^b on a shaft 23^c. This shaft 23^c carries two pinions 24 and 25, which mesh respectively with corresponding pinions 26 and 27 mounted on the skew shafts 7 and 8, respectively (see Fig. 2).

The operation of the machine will be readily understood. The rod, bar or pipe, designated at A being fed through the rolls, is rigidly held against any lateral movement between the two sets of rolls 3 and 4 and 5 and 6, and is subjected to pressure from the intermediate roll 17. The entering end portion of the rod, bar or pipe is straightened between the second set of cross-rolls acting in conjunction with the intermediate pressure roll; while the last end of the rod, bar or pipe is straightened between the first set of cross-rolls acting in conjunction with the intermediate pressure roll. The motor 20 is preferably of the reversing type, so that if the rod, bar or pipe is not perfectly straightened in its first passage through the machine, the motor can be reversed and the rod, bar or pipe run back through the machine in a reversing direction.

Instead of making the longer rolls continuous, they may be formed in two separated sections 3^a, 3^b, as shown in Fig. 7. In this case these two sections and the opposing short roll 4^a constitute one set of cross-rolls the said sections really constituting a single roll.

The advantages of my invention result from the provision of the two separated pairs or sets of cross-rolls, the rod or pipe crossing from one set to the other, and being acted upon intermediate the two pairs or sets by the intermediate pressure roll. In this manner, any lateral movement of the rod or pipe is effectively prevented.

It will be obvious that various changes can be made in the details of construction and arrangement of the various parts. Thus, the shorter cross-rolls and the intermediate pressure roll may be mounted and adjusted in various ways; instead of employing only two sets of cross-rolls, any desired number of sets in excess of two may be employed; all the rolls may be positively driven; any

suitable arrangement of gearing may be provided for positively driving the rolls; and other changes may be made within the spirit and scope of the appended claims.

What I claim is:

1. A straightening machine of the character described, comprising two sets of separated cross rolls arranged in tandem, one roll of each set having two separated bearing portions and the other roll of each set having a bearing portion intermediate the bearing portions of the first-named roll, each set of rolls forming a straightening pass, and said passes coacting to hold the bar or pipe being straightened against movement to one side of the axial line of the passes without auxiliary guiding means; substantially as described. 70

2. A straightening machine of the character described, comprising two separated sets of cross-rolls, the two rolls of each set having working portions opposite each other and forming between them a straightening pass, the axes of said rolls being oblique to the axis of said pass, and an intermediate pressure roll, the corresponding cross-rolls of the two sets having their axes substantially parallel; substantially as described. 80

3. A straightening machine of the character described, comprising two separated sets of cross-rolls, the two rolls of each set having working portions opposite each other and forming between them a straightening pass, the axes of said rolls being oblique to the axis of said pass, and an intermediate pressure roll, the corresponding cross-rolls of the two sets having their axes substantially parallel, and means for positively driving one cross-roll of each set; substantially as described. 90

4. A straightening machine of the character described, comprising two separated sets of cross-rolls, the two rolls of each set having working portions opposite each other and forming between them a straightening pass, the axes of said rolls being oblique to the axis of said pass, and an intermediate pressure roll, one cross-roll of each set being longer than its mate, and the longer roll of each set being positively driven; substantially as described. 100

5. A straightening machine of the character described, comprising two separated sets of concave cross-rolls, the two rolls of each set having working portions opposite each other and forming between them a straightening pass, the axes of said rolls being oblique to the axis of said pass, an intermediate pressure roll, means for positively driving one cross-roll of each set, and means for adjusting the non-driven rolls and also the intermediate pressure roll toward and away from the driven cross-rolls; substantially as described. 110

6. A straightening machine of the character described, comprising two sets of separated cross-rolls arranged in tandem, one roll of each set having two separated bearing portions and the other roll of each set having a bearing portion intermediate the bearing portions of the first-named roll, each set of rolls forming a straightening pass, and said passes coacting to hold the bar or pipe being straightened against movement to one side of the axial line of the passes without auxiliary guiding means; substantially as described. 120

acter described, comprising two separated sets of concave cross-rolls, the two rolls of each set having working portions opposite each other and forming between them a straightening pass, the axes of said rolls being oblique to the axis of said pass arranged in tandem, the two rolls of each pair having their centers opposite each other, and forming a straightening pass between them, and an intermediate pressure roll, means for positively driving one cross-roll of each set, and means for adjusting the non-driven rolls and also the intermediate pressure roll toward and away from the driven cross-rolls, and also for effecting a longitudinal adjustment of said non-driven and pressure rolls; substantially as described.

15 7. A straightening machine, comprising two pairs of cross-rolls, the two rolls of each set having working portions opposite each other and forming between them a straightening pass, the axes of said rolls being oblique to the axis of said pass arranged in tandem, the two rolls of each pair having their centers opposite each other, and forming a straightening pass between them, and a pressure roll intermediate said pairs, there being a free bending space opposite said pressure roll, and the axes of the cross-rolls being oblique to the axis of the pass as well as to each other, and the axis of the pressure roll being substantially parallel to the axis of one cross-roll of each pair; substantially as described.

20 8. A straightening machine, comprising two pairs of cross-rolls, the two rolls of each set having working portions opposite each other and forming between them a straightening pass, the axes of said rolls being oblique to the axis of said pass arranged in tandem, the two rolls of each pair having their centers opposite each other, and forming a straightening pass between them, and a pressure roll intermediate said pairs, there being a free bending space opposite said pressure roll, and the axes of the cross-rolls being oblique to the axis of the pass as well as to each other; substantially as described.

25 9. A straightening machine, comprising two pairs of cross-rolls, the two rolls of each set having working portions opposite each other and forming between them a straightening pass, the axes of said rolls being oblique to the axis of said pass arranged in tandem, the two rolls of each pair having their centers opposite each other, and forming a straightening pass between them, and a pressure roll intermediate said pairs, there being a free bending space opposite said pressure roll, and the axes of the cross-rolls being oblique to the axis of the pass as well as to each other, and the axis of the pressure roll being substantially parallel to the axis of one cross-roll of each pair; substantially as described.

30 10. A straightening machine having two pairs of cross rolls arranged in tandem, one roll of each pair having a reducing taper from each end toward the center to give two separated bearings on the roll for the piece to be straightened, and the other roll of each pair having its effective bearing intermediate the two bearings of the first named roll, the latter roll being reduced in diameter at its central portion to give a free bending space opposite the effective portion of the second roll; substantially as described.

35 11. A straightening machine having two pairs of cross rolls arranged in tandem, one roll of each pair having a reducing taper from each end toward the center to give two separated bearings on the roll for the piece to be straightened, and the other roll of each pair having its effective bearing intermediate the two bearings of the first named roll, the latter roll being reduced in diameter at its central portion to give a free bending space opposite the effective portion of the second roll; substantially as described.

In testimony whereof, I have hereunto set my hand.

PETTER B. ABRAMSEN.
